UNITED STATES PATENT OFFICE.

CLARENCE T. EVANS, OF MILWAUKEE, WISCONSIN, ASSIGNOR TO THE CUTLER-HAMMER MFG. CO., OF MILWAUKEE, WISCONSIN, A CORPORATION OF WISCONSIN.

MOTOR STARTER.

Application filed October 2, 1924. Serial No. 741,104.

This invention relates to motor starters, and is particularly applicable to compensator starters for induction motors.

It has heretofore been found very advantageous to so design analogous starters such as the fuse type of starter for establishment of starting connections upon movement of an operating handle from a normal extreme position into an opposite extreme position and for establishment of running connections upon release of such operating handle, running connections being maintained by a low voltage magnet and being capable of interruption by movement of the starter from running position directly to off or normal position. Among the advantages of such a starter may be mentioned simplicity and ease of operation and a natural delay in the transition from starting connections to running connections.

The present invention has among its objects to provide an improved compensator starter having operating characteristics of the aforesaid fuse starter, or in other words, to provide a compensator starter wherein starting connections are established by movement of an operating handle from a normal extreme position to an opposite extreme position, and running connections are established by release of such handle, the starter having a low voltage magnet associated therewith for maintaining the running connections and being adapted to return directly to neutral position under low voltage conditions.

Another object of the invention is to provide a compensator starter of the aforesaid character including two movable contact elements each having an extreme neutral position, all desired commutations of circuit, including opening thereof, being effected by movement of the elements each from one extreme position to another extreme position and release thereof.

Another object is to provide an exceedingly compact, simple and rugged compensator starter of the aforesaid character having its parts arranged to facilitate inspection and repair thereof and to also facilitate wiring of the starter.

Various other objects and advantages of the invention will hereinafter appear.

The accompanying drawings illustrate an embodiment of the invention which will now be described, it being understood that the

embodiment illustrated is susceptible of modification without departing from the scope of the appended claims.

In the drawing:

Figure 1 is a side elevational view of the compensator starter, the casing and oil receptacle therefor being shown in section.

Fig. 2 is a front elevational view of certain of the parts shown in Fig. 1, the cover for the starter being removed, and the oil receptacle being shown in section.

Fig. 3 is a fragmentary view illustrating the switch mechanism in starting and running positions, and

Fig. 4 is a diagrammatic view illustrating the circuit connections for the starter.

Referring to Figs. 1 and 2, the controller shown therein is particularly adapted to control a three phase alternating current motor, and includes movable contact elements 1 and 2, and a stationary contact element 3. As hereinafter set forth, contact elements 1 and 2 are normally in the extreme positions shown in Fig. 1 and are movable simultaneously to opposite extreme positions shown in full lines in Fig. 3, the contact element 1 being then adapted to cooperate with stationary contact element 3 to establish starting connections for the motor. Contact element 2 is adapted to be releasably held in the extreme position shown in Fig. 3 by a low voltage magnet 4, and in such position the same is adapted to cooperate with contact element 1 upon return of the latter to normal position to establish running connections. Upon release of contact element 2 by the low voltage magnet 4, said element is adapted to return to the position shown in Fig. 1 to interrupt the running connections.

More specifically, contact elements 1 and 2 are provided with rotatable supporting shafts 5 and 6, respectively, said shafts being arranged in a parallel relation and being supported at opposite ends by bearings provided in brackets 7 and 8 fixed to an insulating panel 9. Contact element 3 includes a supporting rod 10 arranged in a parallel relation with respect to shafts 5 and 6 and fixed at opposite ends to brackets 7 and 8. Shaft 5 is provided with a square insulated portion 11 which carries five downwardly extending switch arms, 12 to 16, inclusive, each of said switch arms being secured to the insulated portion of said shaft by a cap member 17. Each of the

arms 12 to 16, inclusive, carries a pair of fingers 18-18, Fig. 1, the lower ends of each of said fingers being provided with a contact tip 19. The fingers 18 of each arm 5 are arranged in opposed relation and are pivotally secured intermediate their ends to their respective switch arms by pins 20. Also, the fingers 18 of each of the switch 10 arms of element 1 are biased to move in opposite directions by a spring 21, such movement being limited by engagement of the upper ends of said fingers with stops 22 on their respective switch arms. Shaft 6 is provided with a square insulated portion 15 carrying three contact arms 23, 24 and 25 arranged as hereinafter described. Each of said arms is secured to shaft 6 by a cap member 26, and is provided with a contact tip 27 on the lower end thereof. Contact 20 element 3 includes five contact supporting arms 28 to 32, inclusive, arranged as herein-after described and each of said arms is secured to a square insulated portion of shaft 10 by a cap member 33 and is provided with a contact tip 34 on the lower end thereof.

The operating means for contact elements 1 and 2 will now be more fully described in connection with Figs. 1 and 2. As shown 30 in these figures, shaft 5 of contact element 1 has an upwardly extending arm 35 fixed thereto, the upper end of said arm being provided with a slot 36 to receive a roller 37 carried by an arm 38. Arm 38 is fixed to 35 a shaft 39 supported within bearings in a bracket 40 mounted on panel 9 and said shaft is bent upwardly as shown in Fig. 2, and carries an operating handle 41 on the upper end thereof. Shaft 5 also has a 40 second upwardly extending arm 42 fixed thereto, the free end of said arm being operatively connected to contact element 2 through the medium of an arm 43 fixed to shaft 6 and a link 44 pivotally connected to the free end of arm 42. Link 44 is operatively 45 connected to arm 43 through the medium of a lost motion connection comprising an elongated slot 45 in said link and a pin 46 fixed to the free end of arm 43.

The arrangement is such that upon movement of handle 41 in a clockwise direction from the normal extreme position illustrated in Fig. 1 to the extreme position illustrated in Fig. 3 contact element 1 is moved to the 55 extreme position illustrated in full lines in Fig. 3 through the medium of levers 35 and 38, and during such movement of contact element 1 contact element 2 is also moved from the extreme position shown in Fig. 1 to the position shown in Fig. 3 through the medium of arm 42, link 44 and arm 43. As before stated contact element 2 is adapted 60 to be releasably held in the position shown in Fig. 3 by the low voltage magnet 4 and it is apparent when the same is held in such

position the lost motion connection between link 44 and arm 43 permits return of contact element 1 to normal position. Also it is apparent that said lost motion connection permits return of contact element 2 to normal 70 position after return of contact element 1 to its normal position.

The low voltage release magnet 4 is provided with a U-shaped frame 50 having an armature member 51 pivotally secured thereto. Magnet frame 50 is carried by a bracket 52 fixed to panel 9 and armature member 51 is provided with a hooked projection 56 to engage pin 46 on arm 43 of contact element 2 when the latter is moved 80 to the position shown in Fig. 3. In the arrangement shown contact element 1 is biased to move to its normal position by a spring 57 having one end fixed to arm 35 and its opposite end fixed to bracket 8 while contact element 2 is biased towards its neutral position by a weighted portion 58 on arm 43.

The circuit connections of the aforedescribed compensator starter will now be more fully described in connection with Fig. 4. As shown in this figure, the starter is adapted to establish starting and running connections for a polyphase motor M from a three phase circuit indicated by lines L¹, L², and L³. Lines L¹, L² and L³ are permanently connected to switch arms 12, 14 and 16, respectively, of contact element 1, and the switch arms 12 and 16 are permanently connected to contact arms 23 and 25 of contact element 2. The terminals M¹ and M³ of motor M are permanently connected to switch arms 13 and 15 of element 1, while the intermediate terminal M² of the motor is permanently connected to switch arm 24 of element 2 and contact arm 30 of element 3. Contact arms 28 and 32 are connected to one terminal of compensator windings C¹ and C², respectively, and the opposite terminals of said windings are both connected to terminal M² of the motor. Also, the compensator windings C¹ and C² are provided with intermediate taps connected to contact arms 29 and 31, respectively, of stationary contact element 3.

The electrical connections made between the supply circuit and the motor when the contact element 1 of the starter is moved into engagement with the contacts of the stationary contact element 3 and out of engagement with said stationary contact element and into engagement with the contacts of element 2 are apparent to those skilled in the art, and it is sufficient to state that in the starting position of the compensator, winding C¹ is connected across phase L¹-L² while compensator winding C² is connected across phase L²-L³ and by reason of the connection of terminals M¹-M³ of the motor to the intermediate taps of the compensator windings the motor will receive less than the

full potential of the supply line. In the running position of the starter the terminals of the motor are directly connected to supply lines L^1 , L^2 and L^3 through engagement of the contacts of element 1 with the contacts of element 2, and the motor will thus be supplied with full line potential.

As shown in Fig. 4 the low voltage magnet 4 is connected between line L^1 and terminal M^2 of the motor through the medium of a normally closed push button P. B., and the armature 51 will thus be attracted to hold contact element 2 in the position shown in Fig. 3 immediately upon establishment of running connections, circuit being established from line L^1 through said push button and said magnet to the motor terminal M^2 and thence to line L^2 through contact arms 30 and 14 of the starter. As before stated, contact element 2 is maintained in the extreme position shown in Fig. 3 during the change over from starting to running, and it is therefore necessary to maintain magnet 4 energized during such change over. This can be readily accomplished by adjusting the fingers 18 of contact arm 14 so that the same will momentarily bridge switch contact arms 30 and 24 during the change over from starting to running.

The no voltage magnet 4 can be controlled by other means than that shown in the drawing, as, for example, by auxiliary contacts controlled by the starter mechanism, and it is also apparent that the contact arrangement of the starter can be modified if desired.

As before stated, the switch mechanism is supported on a panel 9 and as shown in Fig. 1 said panel is fixed to a casing 60 by suitable brackets 61. Casing 60 is provided with hinged cover 62 and said casing is of such dimensions as to permit mounting of the compensator windings C^1 and C^2 therewithin and above the switch mechanism. The compensator windings C^1 and C^2 can be of usual construction, the same being provided with the usual current taps, and having a core structure which is secured in a suitable manner to the casing 60. It is also desirable to provide for oil immersion of the control contacts and for this purpose an oil receptacle 63 is provided which is adapted to be suspended from the brackets 7 and 8 by releasable clamping devices 64 illustrated in Fig. 5.

In connection with the foregoing, it should be noted that the cover 62 and oil receptacle 63 can be readily removed for inspection or repair of the compensator, and it should be also noted that by designing the casing member 60 as shown in Fig. 1 a clear space is provided to the rear of panel 9 and to the rear of the compensator windings. Thus, the required connections can be brought in, through openings 65 in lower end of casing

60, or through openings 66 in the upper end thereof, and such taps can be connected to suitable terminals mounted on insulating panel 9.

While the aforescribed starter has been shown as provided with manual operating means, the same can be readily operated electromagnetically if desired. To provide for electromagnetic operation of the compensator it is merely necessary to employ a magnet for operating shaft 39, such magnet when energized being adapted to rotate said shaft in clockwise direction, Fig. 1, for establishment of starting connections, and when deenergized to permit reverse rotation of said shaft for establishment of running connections.

What I claim as new and desire to obtain by Letters Patent is:

1. A compensator starter for induction motors, comprising cooperating contacts and operating means therefor including an actuating part having an extreme neutral position and being movable to another extreme position to effect establishment of starting connections, and an electromagnet for restraining certain of said contacts against movement whereby running connections are established upon release of said actuating part subject to interruption of such connections upon failure of voltage, said contacts including contacts carried by movable elements each biased to an extreme position for interruption of both starting and running connections.

2. A compensator starter for induction motors, comprising cooperating contacts to establish starting connections and running connections and to interrupt both said connections including contacts carried by movable elements each biased to an extreme position to effect interruption of both starting and running connections, operating means for said elements whereby movement of both elements to their opposite extreme positions and release of said elements progressively effects progressive establishment of starting connections, interruption of starting connections and establishment of running connections and interruption of both starting and running connections, and a low voltage magnet for holding one of said elements in an extreme position to maintain running connections pending deenergization of said magnet.

3. A compensator starter for induction motors, comprising cooperating contacts, certain being movable and being engageable and disengageable with one another to establish and interrupt running connections and certain being stationary and being adapted to cooperate with certain of said movable contacts to establish starting connections.

4. A compensator starter for induction motors, comprising a movable contact ele-

- ment, contacts to cooperate with said element in one extreme position thereof to establish starting connections and other contacts to cooperate with said element in an opposite extreme position thereof to establish running connections, said latter contacts being movable to interrupt running connections while said element is maintained in its last-mentioned extreme position.
10. 5. A compensator starter for induction motors, comprising a movable contact element, contacts to be engaged by said element upon movement thereof into one extreme position to establish starting connections, contacts to be engaged by said element upon movement thereof into an opposite extreme position to establish running connections, and means associated with said last mentioned contacts to move the same out of engagement with said contact element for interruption of said running connections.
15. 6. In a compensator starter for induction motors, in combination a plurality of stationary contacts, and a plurality of movable contacts each movable from a normal extreme position into an opposite extreme position, certain of said movable contacts being adapted in their opposite extreme position to engage said stationary contacts for establishment of starting connections, and certain other of said movable contacts being adapted in their normal positions to cooperate with certain other of said movable contacts in their opposite extreme positions to establish running connections.
20. 7. A compensator starter for induction motors, comprising a plurality of stationary contacts and a plurality of movable contacts each biased toward a normal extreme position and movable into an opposite extreme position, certain of said movable contacts being adapted in their opposite extreme position to engage said stationary contacts for establishment of starting connections and certain other of said movable contacts being adapted in their normal position to cooperate with the other of said movable contacts in their opposite extreme positions to establish running connections, said last mentioned contacts being adapted upon return to normal position to interrupt said running connections.
25. 8. In a motor controller, in combination, two separately movable contact elements each normally tending to move to one extreme position and movable to an opposite extreme position, one of said elements being adapted in its latter extreme position to establish starting connections and also being adapted in its normal position to cooperate with the other of said elements in its opposite extreme position to establish running connections, and electromagnetic means for restraining said last mentioned element in its opposite extreme position, subject to automatic release under predetermined conditions.
30. 9. In a motor controller, in combination, two contact elements each normally tending to stand in a given extreme position and being movable to an opposite extreme position, one of said elements in its opposite extreme position being adapted to establish starting connections, and the other being adapted in its opposite extreme position to cooperate with the former element in the normal position thereof to establish running connections, a common operating member for said elements providing for simultaneous movement thereof into their opposite extreme positions, and permitting return of the first mentioned element to its normal position independently of the other element, and electromagnetic means for restraining said latter element in its opposite extreme position subject to automatic release under predetermined conditions.
35. 10. In a motor controller, in combination, two sets of movable contacts, a set of stationary contacts, one set of said movable contacts being adapted to cooperate with said stationary contacts to establish starting connections and being also adapted to cooperate with the other set of said movable contacts to establish running connections, operating means for said movable contacts including a member having an extreme position corresponding to starting relation of said contacts and another extreme position corresponding to running relation of said contacts, said means insuring cooperation of said contacts in starting relation prior to their cooperation in running relation, and said contacts being returnable directly from running relation to neutral relation while said member is maintained in its last mentioned position, and electromagnetic means for holding certain of said contacts in a given extreme position upon establishment of running connections.
40. 11. In witness whereof, I have hereunto subscribed my name.

CLARENCE T. EVANS.
